Primary Examiner — George J Ulsh*Assistant Examiner* — Kathryn Elizabeth Zieno(74) *Attorney, Agent, or Firm* — Kilpatrick Townsend & Stockton LLP(57) **CLAIM**

The ornamental design for a pool skimmer adapter plate as shown and described.

DESCRIPTION

FIG. 1 is a rear perspective view of a pool skimmer adapter plate showing our new design.

FIG. 2 is a front elevation view thereof.

FIG. 3 is a rear elevation view thereof.

FIG. 4 is a top view thereof, the bottom view being a mirror image thereof; and,

FIG. 5 is a right-side elevation view thereof, the left-side elevation view being a mirror image thereof.

The broken lines shown in the FIGS. 1 through 5 are included for the purposes of illustrating environment and form no part of the claimed design.
